UNITED STATES PATENT OFFICE.

IGNATIUS MAISANO, OF WILMINGTON, DELAWARE.

TOY.

1,359,817.

Specification of Letters Patent. Patented Nov. 23, 1920.

Application filed February 26, 1920. Serial No. 361,569.

To all whom it may concern:

Be it known that I, IGNATIUS MAISANO, a citizen of the United States, residing at Wilmington, in the county of New Castle 5 and State of Delaware, have invented new and useful Improvements in Toys, of which the following is a specification.

This invention relates to toys for the amusement of children, and more particularly to a mechanical toy of the Ferris wheel type in which a wheel rotates in a vertical plane and carries with it a plurality of suspended seats or baskets wherein dolls and other playthings may be placed; the wheel 10 being turned by means of a crank, while a second crank, connected to a jointed figure, moves the latter whereby to suggest that such figure is turning the wheel or aiding the operator. To afford additional amusement a plurality of bells are arranged to be sounded by the rotating wheel.

The invention consists in the combination and arrangement of parts hereinafter described, and more especially as set forth in 25 the claims and illustrated in the accompanying drawings in which—

Figure 1 is an elevation of my improved toy; and Fig. 2 an elevation viewed at a right angle to Fig. 1. 30 10 is a base of circular or other form, from which rises two spaced standards 11 preferably ornamental in outline and suitably embellished. Between the standards 11 is a Ferris wheel 12 formed of two disks 13 which are mounted on the ends of a hub 14 fixed upon an axle 15, the latter having bearings in the standard 11. Between the disks 13 of the wheel 12 are a number of 35 equally spaced rods 16 from each of which is freely suspended by arms 17 a basket or seat 18 in which dolls or other playthings may be put to ride with the revolving wheel 12. The ends of the axle 15 pass through the standards 11 and are bent to form the 40 cranks 19 and 20, the former or main one being employed to turn the wheel 12. Pivoted to the supplemental crank 20 are the hands of a jointed human figure 21, its arms 45 22 being pivoted to its body 23, while the

latter in turn is pivoted at 24 to the stationary legs 25, they being secured to the base 10 or to a bracket 26 projecting therefrom.

When the wheel 12 is turned by means of the crank 19, the crank 20 will cause the figure 21 to move in a more or less natural 55 way and convey to the user the idea of receiving assistance by another person turning the wheel.

A brace 27 of triangular or other shape connects the tops of the standards 11, the apex of the brace having an ornament 28 to which are attached flags 29. Flags 30 may be displayed at other suitable points on the standard as shown.

Attached to the under side of the brace 65 27 are a plurality of bells 31, the clappers 32 lying in the path of the rods 16, so that as the wheel 12 rotates the rod 16 will strike the clappers 32 and cause the ringing of the 70 bells.

The general arrangement is such that when the wheel 12 is turned by means of a crank 19, the baskets 18, swinging from the rod 16, travel in a circular path, the bells are rung, and the figure 21 appears to be 75 turning the wheel.

I claim:

1. In a toy, the combination of a base, standards fixed to said base and extending upwardly therefrom, a wheel comprising 80 two disks and having spaced rods connecting them, said wheel being journaled in said standards, a plurality of swinging baskets or seats carried by said wheel, a main crank for rotating the wheel, a second or supplemental crank rotatable with the wheel, a jointed figure pivotally connected to said second crank and movable as the main crank is rotated, and a plurality of bells adapted 85 to be sounded by the spaced rods of the rotating wheel.

2. In a toy, the combination of a base, spaced standards fixed to said base and extending upwardly therefrom, an axle journaled in said standards and having a main 95 crank at one end and a supplemental crank at the other end, a wheel formed of two disks, and a hub fastened to said axle be-

tween the standards, a plurality of spaced rods extending between the wheel disks, a basket or seat swinging freely from each rod, a jointed figure fixed on the base and 5 pivotally connected to said second crank, a brace connecting the tops of said standards, and bells attached to said brace, the clappers or hammers of which bells are

adapted to be struck by said spaced rods of the wheel when the latter is rotated. 10

In testimony whereof I affix my signature in presence of two witnesses.

IGNATIUS MAISANO.

Witnesses:
